United States Patent

Des. 237,734
Patented Nov. 18, 1975

237,734

PENDANT OR SIMILAR ARTICLE

Margareta C. Roberts, Providence, R.I., assignor to Reed and Barton Corporation, Taunton, Mass.

Filed May 23, 1974, Ser. No. 472,832

Term of patent 14 years

Int. Cl. D11—01

U.S. CL. D45—19 L

FIG. 1

FIG. 2

FIG. 3

FIG. 4

FIG. 5

FIG. 1 is a front elevational view of a pendant or similar article showing my new design;

FIG. 2 is a rear elevational view thereof;

FIG. 3 is a right side elevational view thereof;

FIG. 4 is a top plan view thereof; and

FIG. 5 is a bottom plan view thereof.

I claim:

The ornamental design for a pendant or similar article, substantially as shown.
